2 Sheets-Sheet 1

A detailed technical line drawing of a mechanical assembly, possibly a pump or valve mechanism. The drawing is oriented vertically and features several vertical and horizontal components. Key parts include a central vertical rod (1), a horizontal rod (2) extending from the left, and a base assembly (3) at the bottom. Numerous small components are labeled with numbers such as 1, 2, 3, 6, 11, 12, 13, 14, 15, 16, 17, 18, 19, 20, 21, 22, 23, 24, 25, 26, 27, 28, 29, 30, 31, 32, 33, 34, 35, 36, 37, 38, 39, 40, 41, 42, 43, 44, 45, 46, 47, 48, 49, 50, 51, 52, 53, 54, 55, 56, 57, 58, 59, 60, 61, 62, 63, 64, 65, 66, 67, 68, 69, 70, 71, 72, 73, 74, 75, 76, 77, 78, 79, 80, 81, 82, 83, 84, 85, 86, 87, 88, 89, 90, 91, 92, 93, 94, 95, 96, 97, 98, 99, and 100. The drawing uses various line weights and cross-hatching to differentiate parts and show assembly details.

UNITED STATES PATENT OFFICE

VIRGIL WRIGHT, OF DALLAS, TEXAS, ASSIGNOR OF ONE-THIRD TO AGNES HIGH, OF DALLAS, TEXAS

MACHINE FOR CUTTING GASKETS

Application filed August 23, 1928. Serial No. 301,625.

The present invention is directed to improvements in machines for cutting gaskets, and more particularly from sheets of asbestos.

The primary object of the invention is to provide a device of this character so constructed that a sheet of asbestos may be conveniently placed in proper relationship with respect to a pair of revolving cutters in order that a complete gasket will be quickly 10 cut.

Another object of the invention is to provide a device of this character so constructed that the sheet of material from which the gaskets are cut will be automatically fed 15 during the cutting operation.

Another object of the invention is to provide a device of this character which is simple in construction, compactly arranged, durable, and one which can be manufactured at a 20 small cost.

With these and other objects in view, this invention resides in the novel features of construction, formation, combination and arrangement of parts to be hereinafter more 25 fully described, claimed and illustrated in the accompanying drawings, in which:—

Figure 1 is a longitudinal sectional view through the device, parts thereof being shown in elevation.

Figure 2 is a sectional view on line 2—2 of Figure 1.

Figure 3 is a sectional view on line 3—3 of Figure 1.

Referring to the drawings, 1 designates a 35 top of a table having bolted to one end thereof upper and lower bearing sleeves 2 and 3 in which is journaled the driving shaft 4. The upper sleeve 2 carries a bracket 5 having a bearing 6, said bearing receiving the shaft

40 4. This bracket has formed integral therewith a horizontally disposed tubular arm 7 to which is secured the lower end of the brace rod 8, the upper end of which is secured to the collar 9 rotatably engaged upon the 45 extended end of the shaft 4.

Rotatable in the arm 7 is a shaft 10 to the rear end of which is fixed a bevel gear 11 which meshes with a similar gear 12 fixed to the lower end of the shaft 4. A U-shaped 50 frame 13 is provided and has its arms 14—14

provided with bearings 15—15 adapted to slidably engage the shaft 10.

Slidably keyed to the shaft 10 is a bevel gear 16 which meshes with a similar gear 17 on the vertical shaft 18 journaled in the bearing 19 of the frame 13. The lower end of the shaft 18 has adjustably secured thereto a cutting disk 20, the purpose of which will be later explained.

Upper and lower brackets 21 and 22 are 60 bolted to the table 1 and are provided with bearings 23 and 24, respectively, the former receiving the outer ends of the shaft 10. The bracket 21 has formed integral therewith a horizontal arm 25 in which is formed a longitudinal slot 26, there being a similar arm 27 carried by the bracket 22 which is also provided with a longitudinal slot 28. The arms 14 of the frame are adjustably secured to the arm 25 by bolts 29—29 in order that 65 said frame may be fixed in adjusted position on the shaft 10.

The bearing sleeve 3 has a bracket 29' which is provided with the bearings 30 and 31, the former having journaled therein the 75 inner end of the shaft 32, the outer end of which is journaled in the bearing 24. This shaft has fixed to its inner end a bevel gear 33 which meshes the similar gear 34 fixed to the lower end of the drive shaft 4.

A stub shaft 35 is journaled in the bearing 31 and has fixed to its outer end a relatively large bevel gear 36 which meshes with the gear 34, said shaft also having fixed thereto a belt pulley 37 in order that power from a suitable source may be used for driving the device. A detachable handle 38 may be secured to the gear 36 when it is desired to drive the device manually.

A frame 39 is provided, and has a head 40 90 for slidably engaging the underside of the table 1, said head having a bearing 41 in which is journaled a shaft 42, said shaft having fixed to its lower end a bevel gear 43 which meshes with the gear 44 slidably keyed 95 to the shaft 32, the gears 43 and 44 being arranged between the arms 45—45 of the frame 46 carried by the lower end of the head 40. The arms 45—45 are provided with bearings 47—47 for slidably engaging the 100

shaft 32. The arms 45 have carried thereby bolts 48-48 which engage in the longitudinal slot 28 of the arm 27, and like the bolts 29 serve to hold the frame 46 in adjusted position upon the shaft 32.

5 The shaft 42 extends through a slot 49 formed in the table 1 and has fixed to its upper end a cutting disk 50.

The table 1 has formed longitudinally 10 therein a centrally disposed groove 51 in which is slidable a metallic block 52, said block having a socket 53 formed therein for receiving the lower end of the centering pin 54. This pin is carried by a sleeve 55 vertically adjustable on the angle arm 56 carried by the sleeve 57, said sleeve being slidably adjustable on the graduated portion of the arm 7, said sleeve being held in adjusted position by the set screw 58.

20 In operation a sheet 59 of asbestos is placed upon the table and the centering pin 54 passes therethrough for engagement with the socket 53 of the block. The cutting disk 20 is elevated and the sheet 59 is placed over the cutting disk 50, after which the cutter 20 is 25 lowered so that its cutting edge will coact with the cutting edge of the cutter 50 during rotation of the disk. Obviously when the shafts 10 and 32 are driving the gears, one 30 cutting disk will rotate clockwise while the other will rotate counter clockwise, and since the sheet is engaged between the cutting edges of the disk the rotation of the disk will feed the sheet as the gasket is cut. As shown in 35 Figure 2 the sheet 59 has been cut on the line A, after which the disks are adjusted to cut the sheet on the line B to complete the cutting operation.

It will be of course understood that gaskets 40 of irregular form can be cut, and at which time the centering pin is disengaged from the block and the sheet moved manually to follow irregular paths.

While the device is primarily designed for 45 cutting gaskets from sheets of asbestos, it will be understood that it may be used with equal success for cutting material other than asbestos.

Since the frames 13 and 46 can be 50 conveniently adjusted upon the respective shafts it will be apparent that the cutting disks can be moved to various points upon the table in order that gaskets of various sizes can be conveniently cut and sheets of asbestos varying in sizes may be conveniently handled.

55 From the foregoing, it is thought that the construction, operation and many advantages of the herein described invention will be apparent to those skilled in the art, without further description, and it will be understood that various changes in the size, shape, and proportion and minor details of construction, may be resorted to without departing from the spirit or sacrificing any of the advantages of the invention.

What is claimed is:—

1. A device of the class described, comprising a table, shafts disposed above and below the table, a frame supported by each shaft, cutting disks rotatably supported by each frame, means for adjusting the frames longitudinally upon the shafts, and means for simultaneously rotating the shafts to rotate the cutting disks. 70

2. A device of the class described, comprising a table, a tubular arm supported above the table, a shaft rotatable in the arm, a second shaft rotatably supported below the table, a frame slidably adjustable upon each shaft, a cutting disk rotatably supported by each frame, geared connections between the shaft and cutting disks, and means for rotating the shafts in reverse directions to impart rotary movement through the geared connections to the cutting disks to rotate said disks in reverse direction. 75

80 3. A device of the class described, comprising a table, a pair of horizontally disposed rotatably mounted cutting disks disposed substantially in a horizontal plane with the upper surface of the table, means for adjusting the cutting disks toward or away from each other, and means for simultaneously rotating said disks in reverse directions. 90

95 4. A device of the class described comprising a table, a tubular arm supported above the table, a shaft rotatably mounted in the arm, a second shaft rotatably mounted below the table, a frame mounted upon each shaft, a rotary cutting disk carried by each frame, 100 a pin adjustably connected with the tubular arm and adapted to engage the sheet to be cut by the cutters, and means for simultaneously rotating the cutters in reverse direction. 105

110 5. A device of the class described comprising a table, a shaft journaled above the table, a second shaft journaled below the table, frames slidable on each shaft, rotary cutting disks carried by each frame, means for rotating the disks, arms associated with the shaft, and means carried by the arms and connecting the frames for holding the frames in adjusted position upon the shafts. 120

In testimony whereof I affix my signature. 115
